SIFTER CLOSURE

Robert Nyden, Manhasset, N. Y., assignor to
F. N. Burt Company, Inc., Buffalo, N. Y., a corporation of Delaware

Application July 9, 1942, Serial No. 450,277

7 Claims. (Cl. 221—64)

This invention relates to a container and closure and aims to provide a sifter closure adaptable for dispensing granular or powdered substances such as face and body powder, tooth powder, sugar, flour, salt, pepper, and other similar items.

Containers and closures of this type might generally be referred to as sifter containers and closures, and it is an aim of my invention to provide such a sifter container and closure which may readily be manufactured from paper, cardboard, chipboard, and plastic materials of various types.

Heretofore, many of the containers and closures adapted for the dispensing of materials such as are capable of being dispensed by the present invention, were manufactured from metal or other products, which products are not now readily available for these purposes. The structures of the prior art metal closures do not lend themselves to manufacture from paper, cardboard, chipboard, etc., and accordingly it is a major object of my invention to provide a new closure structure readily fabricated from paper and plastics.

It is a further object of my invention to provide a simplified closure unit which can be completed as a standard unit and applied inexpensively to various types and styles of containers.

In providing the new container and closure of my invention, a major object has been the provision of a structure of utmost simplicity capable of rapid manufacture with a minimum of expense, and utilizing readily available materials particularly non-metallic materials.

The structure by which these and other objects are obtained is illustrated in the accompanying drawing in which:

Fig. 1 is a top view of a container and closure embodying my invention;

Fig. 2 is a vertical section taken along the line 2—2 of Fig. 1 and showing the sifter closure in a closed position;

Fig. 3 is an exploded perspective view of the closure and a portion of the container so that the manner of fabrication and assembly may be more readily visualized;

Fig. 4 is a cross section similar to that of Fig. 2 of a container and closure embodying my invention, and showing a modified form of container;

Figure 5 is a top view of a modified form of my invention and shows certain of the structure broken away for purposes of illustration;

Fig. 6 is an exploded vertical central cross

sectional view of the structure shown in Fig. 5.

The closure of my invention is of a construction readily adapted to fabrication from paper, cardboard, chipboard or plastic materials, and has been designed with a view to efficient manufacture from materials of this type. While this closure may be utilized with containers made of various substances such as metal, glass, or pottery, nevertheless, the structure is such that it is highly adaptable for use with containers made of a material similar to the closure, that is, paper, cardboard, etc.

Referring now to the drawing, Figs. 1 to 3 inclusive, it is noted that I provide a container 10 which may be of any configuration and whose top opening is provided with a securing edge formed by an annular flange 11 provided with an offset shoulder 12.

In order to provide a closure for this container, I form, preferably by die-cutting and punching from sheets of paper, etc., two similar fixed sifters 13 and 14, each provided with openings respectively referred to as 15 and 16, and which openings are capable of being placed in aligned position. While these stationary sifters may be cut from the same thickness of material, it is not necessary that they be so. It is important to note, however, if sifter 13, which I shall refer to as the bottom sifter member, is to be used with a container having a depressed opening similar to that of container 10, then that sifter must be of a thickness greater than the height of the depending or depressed annular flange 11. This bottom sifter member is, of course, of a configuration adapted to be placed and secured within the opening in the top of the container, and, while in the drawing it is shown in circular form, this shape may of course be varied depending upon the size and shape of the container opening.

A manual rotatable sifter 17 adapted for positioning between the fixed sifters 13 and 14 and which may be rotated to open or close the closure openings, is likewise fabricated from paper, cardboard, chipboard or other similar material. Likewise, while its thickness may be of any size, if desired, it may be of the same thickness and of the same material as that forming the stationary sifters 13 and 14.

The rotatable sifter 17 is preferably formed in circular form with either a scalloped or serrated edge 18 to provide a roughened non-slipping finger grip. The diameter or other outside dimension is preferably greater than that of the top sifter member 14 so that the hand of the

user may readily be placed upon the serrated edges for manual rotation. This member is formed with spaced openings 19 so positioned that upon rotation they may be aligned with the complementary openings provided in sifter members 13 and 14. In forming this rotating sifter, a centering and spacing disc 20 is cut from the center thereof, thus providing a circular opening 21 which is adapted for positioning on and rotary movement about a stationary member. This stationary member is preferably formed by utilizing the disc 20 which was cut from the rotating sifter and fixing it against movement between the two fixed sifter members.

In assembling the closure, the separate members may be assembled directly on the container or the entire closure unit can first be completely assembled and then applied to the container in such completed form.

Following this latter assembly method, I first take bottom sifter 13 and center thereon the disc 20 which is then secured thereto by adhesive or other suitable means. Rotating sifter 17 is placed over the centering disc 20, the centering disc 20 engaging the opening 21, and thereupon the rotating disc is free to rotate about the centering disc. Upper sifter 14 is then superimposed upon the centering disc 20 and, after holes or openings 16 are placed in line with openings 15, secured thereto by suitable adhesive or other means.

With the parts now in position, it is quite clear that by a rotation of sifter 17, the holes 19 thereof may be made to fall in or out of alignment with the holes 15 and 16 of the bottom and top sifter members. By this means there is provided as excellent closure for the dispensing of products such as tooth and talcum powder, sugar or other similar substances.

Due to the fact that centering disc 20 was cut from the rotating sifter 17, there has been no waste material, and additionally, the rotating sifter 17, due to its being the same thickness as the disc 20, is given a close fit between the upper and lower stationary sifters. Accordingly, the frictional drag between the adjacent surfaces is such that a relatively tight seal is provided, the resiliency of the material, however, allowing the parts to be readily manipulated into open or closed position at the will of the operator.

Utilization of the disc 20 actually cut from the rotating member is preferred in forming the pivot. This preference is caused by the fact that thereby a uniformity of thickness of the rotary member and its pivot are assured and thus the top and bottom sifter members which are in turn secured to the pivot will be uniformly closely positioned adjacent the rotary member thus providing a seal of the openings but without binding movement of the parts.

The important object is to provide a close resilient seal on both the top and bottom surfaces of the rotating member. Therefore, if desired, and if care is exercised in providing the proper thickness of pivot, the pivot may be formed from other material than that used for the rotating member. Likewise, and if desired, the pivot may also be formed integral with the top or bottom sifters or as part of the top of the container.

In assembling the closure and the container, the method generally is to secure the bottom sifter 13 in position over the opening provided. If the container is one having a depressed opening similar to that illustrated in Figs. 1, 2, and 3, then bottom sifter 13 is placed in position resting upon shoulder 12 and secured thereon either by frictional engagement with flange 11 or by adhesive or other suitable means.

Fig. 4 shows a closure structure similar to that shown in Figs. 1 to 3, but applied to a container having a different configuration. This container 22 has an upper inclined or tapered portion 23 in the top of which the closure portion is inserted. The formation of the depressed annular flange 24 as well as the retaining shoulder 25 is similar to the previously described structure. The bottom sifter 26 is provided with openings 27 which are adapted to align with the openings 28 of the top sifter 29, as well as the openings 30 of the rotating sifter 31. As shown in Fig. 4, all of the openings are aligned and the container is in a position to dispense the product in it.

In the type of structure shown in Figs. 5 and 6, a single sifter opening is provided in the closure. This type of single opening is readily adaptable for use in the dispensing of tooth powder and other similar substances requiring distribution over a relatively small area.

Except for the provision of the single holes 32, 33, and 34, respectively, in the bottom sifter 35, top sifter 36 and rotating sifter 37, the structure is essentially the same as that shown in Figs. 1, 2, and 3. It is, of course, to be observed that the bottom sifter 35 is of a thickness greater than the depth of the depressed annular flange 38, so that the rotating sifter 37 will be free to rotate on the top surface of the bottom sifter 35. As shown, the upper sifter 36 is considerably thinner than the bottom sifter 35. While this structure permits the use of less stock material, it is to be understood that the thickness of the various parts may, within the limits of my invention, be varied.

While I have, for purposes of illustration, described a sequence of assembly of parts, it is to be understood that the sequence may be varied without departing from my invention.

Thus, it will be seen that the structure of my invention provides a dispensing device which is simple, rugged, inexpensive to manufacture, and readily adaptable to fabrication from non-metallic materials, more particularly those referred to above.

I claim:

1. In a container closure, in combination, a plurality of spaced fixed sifter members having aligned dispensing openings, a rotary sifter member positioned between said fixed sifter members and having a mounting opening and also a dispensing opening positioned to be moved into or out of alignment with said first mentioned aligned dispensing openings to open or close the same upon rotation of said rotary sifter member, and a mounting and spacing member having opposite surfaces contacting respectively with the inner surfaces of said fixed sifter members so as to hold the fixed sifter members in spaced relation, said mounting and spacing member being attached to both of said fixed sifter members to secure them together immovably in spaced relation, said mounting and spacing member extending through said mounting opening of said rotary sifter member to rotatably mount the same.

2. In a container closure, in combination, a plurality of spaced fixed sifter members having aligned dispensing openings, a rotary sifter member positioned between said fixed sifter members and having a mounting opening and also a dispensing opening positioned to be moved into or out of alignment with said first mentioned

dispensing openings upon rotation of said rotary sifter member, and a mounting and spacing flat disk having opposing surfaces juxtaposed respectively with the adjacent surfaces of said fixed sifter members and attached to said fixed members to secure them together immovably in spaced relation, said flat disk extending through said mounting opening of said rotary sifter member to rotatably mount the same.

3. In a container closure, in combination, a plurality of spaced sifter members having aligned dispensing openings, a rotary sifter member positioned between said fixed sifter members and having a mounting opening and also a dispensing opening positioned to be moved into or out of alignment with said first mentioned dispensing openings upon rotation of said rotary sifter member, and a mounting and spacing flat disk having opposing surfaces juxtaposed respectively with the adjacent surfaces of said fixed sifter members and adhesively secured thereto to space said fixed members and to secure them together immovably in spaced relation, said flat disk extending through said mounting opening of said rotary sifter member and being substantially the same thickness as the latter so as to rotatably mount the same and to provide for frictional controlling engagement of the rotary sifter member with the fixed sifter members.

4. In a container closure, in combination, a plurality of spaced sheet members one of which has a dispensing opening, a movable closure member positioned between said spaced sheet members and being movable into opening and closing relation with said dispensing opening, said movable closure member having a mounting opening, and a mounting and spacing member having opposite surfaces respectively contacting with the inner surfaces of said spaced sheet members so as to support the latter in spaced relation and being attached to both of said sheet members to secure them together in spaced relation as a unit, said mounting and spacing member extending through said mounting opening of said movable closure member to movably mount the same for opening and closing movements.

5. In a container closure, in combination, a plurality of spaced sheet members one of which has a dispensing opening, a movable closure member positioned between said spaced sheet members and being movable into opening and closing relation with said dispensing opening, said movable closure member having a mounting opening, and a mounting and spacing member positioned between said sheet members and having opposite surfaces respectively juxtaposed and adhesively attached to the adjacent surfaces of the spaced sheet members to space the latter and to secure them together in spaced relation as a unit, said mounting and spacing member extending through said mounting opening of said movable closure member to movably mount the same.
6. In a container closure, in combination, a container wall having an opening and a surrounding depressed flange forming a seat depressed below the outer surface of the wall, a plurality of spaced sheet members one of which has a dispensing opening and is secured in said depressed seat, a movable closure member positioned between said spaced sheet members and being movable into opening and closing relation with said dispensing opening, said movable closure member having a mounting opening, and a mounting and spacing member positioned between said sheet members and attached thereto to space them and to secure them together in spaced relation as a unit, said mounting and spacing member extending through said mounting opening of said movable closure member to movably mount the same.
7. A method of making a container closure including: removing from a sheet member a disk-like part so as to provide in the sheet member an opening substantially the size and shape of the removed part; placing said removed disk-like part in said opening in the sheet member and securing the disk-like part to overlying and underlying sheet closure members thus to movably mount the first mentioned sheet member between the overlying and underlying sheet members.

ROBERT NYDEN.
